UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPEWRITER DESK.

Application filed December 2, 1921. Serial No. 519,313.

This invention relates to desks for type-writing machines, and particularly to those in which the machine may be dropped or swung down and back out of the way at the same time that the top of the desk is closed or completed, by means of a lid or leaf which swings up to a position level with the desk top.

The invention is for the benefit of users of noise-deadening hoods or casings for type-writing machines, as set forth, for example, in the application of George W. Campbell, No. 510,726, filed October 27, 1921. The casing comprises side overhanging portions which accommodate the travel of the type-writer-carriage. A casing such as shown in said application can be located on a type-writer-desk having a well of ordinary proportions; but the present improvements comprise a casing for an extra wide carriage machine, and a casing having at its sides correspondingly prolonged overhanging extensions. Such a casing is too wide to drop into the well of the ordinary typewriter-desk. The invention makes provision whereby such result can be accomplished.

The desk usually comprises two pedestals, each carrying a set of drawers, and also comprises a platform which is occupied by the typewriting machine, and usually swings downwardly and back between said pedestals. According to the present improvements, the typewriter and its sound-deadening casing stand upon such a platform, and the casing overhangs the pedestals. The carriage may be so long and the room needed therefor may be so great, that the overhanging portions of the casing may extend nearly the entire width of the desk top.

The typewriter-keyboard occupies the usual front position in such a casing, and the keys are a few inches below the top of the desk. The overhanging portions of the casing or hood clear the desk top. When it is desired to lower the machine and casing, they are slid back on the platform while the latter remains stationary, the typewriter and casing being for this purpose attached to a baseboard extending across the platform and slideable forward and back therealong in suitable guides. After the machine is thus slid back, the operator grasps the lid or movable portion of the desk and pulls it

up in the usual manner, and swings it into a position level with the remainder of the desk top, thus completing the same. The machine during this operation swings down, and the overhanging extensions drop into auxiliary rear wells provided at the sides of the desk in the upper portions of the pedestals. The movable lid of the desk is shaped to cover these side wells, so that the top of the desk is completed.

When it is desired to use the typewriting machine, the lid of the desk may be lifted and swung or floated back and down into the rear part of the desk structure, thereby elevating the platform from an inclined to a level position, together with the typewriting machine and its hood, and then the machine and hood may be slid to the front part of the platform ready for use.

When the platform or typewriter support is in raised position, it serves to cover the central or main well. To cover the side wells when the machine is in use, provision may be made of a member hinged to the rear edge and shiftable either to an effective position to cover the side wells or to an ineffective position at the back of the desk.

Other features and advantages will hereinafter appear.

In the accompanying drawings,

Figure 1 is a front perspective view of the sound-deadening casing and typewriter-desk therefor, portions being broken away to disclose underlying parts.

Figure 2 is a part-sectional front elevation of the desk with the hood or casing and the typewriting machine raised to working position.

Figure 3 is a sectional side elevation, showing the typewriting machine and hood depressed, and the desk lid level with the remainder of the desk top. This view also shows an auxiliary lid.

Figure 4 is a view similar to Figure 3, but showing the typewriting machine and hood elevated and in forward or working position. The same is shown in dotted lines as shifted to the rear preparatory to dropping into the main and auxiliary wells.

Figure 5 is a view of the top of the desk when the typewriter-support is in raised position and the typewriter and hood removed, the side wells being covered by a

member which is hinged on the desk top at its rear edge and normally hangs at the rear of the desk.

The desk comprises a top 10 and side pedestals 11 and 12, between which is a main well 13. Occupying a position in the upper part of the well is a platform 14, upon which rests a baseboard 15 extending from side to side thereof; and attached to said baseboard 10 in any usual or suitable manner, are a typewriting machine 16 and a sound-deadening hood 17 encasing the same. There is visible the front of the base portion of the typewriter, which protrudes forwardly from the 15 casing and carries the typewriter keys 18.

The typewriter casing comprises a base portion 19, which occupies a position between the pedestals 11, 12 of the desk and rises from the platform 14, and also comprises upper overhanging side extensions 20, which may in some cases extend nearly the width of the desk, as in Figure 2.

When it is desired to lower the typewriting machine and casing, the same are slid 25 back, together with the baseboard 15, which slides upon the platform 14 and works between guides 21, each provided with a keeper 22 overlying the projecting side portion of the baseboard. To avoid noise and facilitate 30 the sliding movement, the top of the platform 14 or the bottom of the baseboard 15 may be faced with felt or other suitable smooth, noise-deadening material (not shown). The machine is pushed back to the 35 dotted line position at Figure 4, the extent of movement of the machine forward and backward being limited by front and rear stop portions 23 formed on the guides. Thereupon the operator grasps the projecting end of a desk lid 24, which temporarily 40 occupies a vertical position at the rear of the desk between the sets of drawers and the rear wall 25 of the desk, and pulls up said top in a manner known in the art, with the result that the platform 14 swings down to the 45 Figure 3 position, the lid being swung or floated forwardly to the level position at Figure 3, thereby filling the openings and completing the desk top.

Said desk lid 24 swings upon lower long arms 26, pivoted at 27, and upper short arms or links 28, pivoted at 29 upon the tops of standards or brackets 30 fixed to the desk. By means of these arms 26, 28, the lid is 50 floated upwardly and forwardly to the closing position. Each arm 26 forms part of a lever having a short arm 31 connected by a vertical link 32 to an arm 33 connected to the platform 14. By means of link 32 and arm 33, the motion of the typewriter platform 14 is controlled. The weight of the desk lid 24 at the Figure 4 position is sufficient to counterbalance the platform 14 and the typewriter and casing thereon when in 55 the rearward dotted line position at Figure

4; although, if desired, the desk lid 24 may be weighted to give more counterbalance, or a counterbalancing spring 34 may be employed.

To accommodate the side extensions 20 of the casing, side wells or well enlargements 35 are formed in the desk and communicate with the main well 13; and the cutaways in the desk top are closed by wings or side extensions 36 formed on the opposite sides of the desk lid, Figure 1, so that the desk top presents a neat appearance when the lid is closed. The provision of the side wells in the desk makes it necessary to reduce the drawer capacity of the pedestals, as seen at 70 Figures 1, 3 and 4, each pedestal having an opening 37 in the upper rear portion thereof sufficient to accommodate one of the side extensions of the typewriter hood. This makes it necessary to shorten the upper two 75 drawers 38, 39 in each pedestal. The main well and the side wells open into the usual well 40 at the back portion of the desk, which accommodates the lid 24, Figure 4. The lower drawers 41, 42 may be of the usual 80 length.

For the lid there is employed a link motion, notwithstanding the fact that the extensions 20 of the typewriter hood pass down into the space usually occupied by such link motion. The linkages are placed at the outer sides of the pedestals, in wells 43 between the sides 44 of the desk and the outer sides 45 of the pedestals 11, 12. The levers 26 are pivoted to the walls 45 of the pedestals, and at their rear ends said levers are pivoted to brackets 46 upon the wings 36 of the lid 24. The arms 33 are mounted upon rock-shafts 47, which are journaled in bushings 48 in the pedestal wells, said rock-shafts carrying at their inner ends arms 49 in the main well 13, these arms being fastened to the under side of the platform 14. In order to secure room for the rock-shafts 47, the upper drawers 38 are made shallow, 95 Figure 2, and horizontal chambers below said drawers are occupied by the rock-shafts, said chambers being closed at their front ends by panels 50. Thus the lid is suitably floated at front and rear upon suitable linkages, while provision is made for ample room for the descent of the extensions 20 of the typewriter hood. 100

If desired, the side wells or extensions 35 may be temporarily closed by a flap 51, 110 which may be hinged at 52 to a pair of brackets 53 at the rear of the desk top. This flap may hang down in rear of the desk, as at Figure 3, when the typewriting machine is out of use, and it may be swung upwardly 115 and forwardly to cover the openings 35 when the typewriter is in the position of use seen at Figures 1 and 4. This temporary lid comprises two similar side portions joined by an intervening portion 54. 120

Variations may be resorted to within the scope of the invention, and portions of the improvements may be used without others.

Having thus described my invention, I claim:

1. In a typewriter-desk, in combination, two pedestals, each containing a set of drawers, spaced apart to form a well therebetween, a desk-top having a T-shaped opening extending rearwardly from the front edge of the desk-top over said well and having lateral extensions at its rear end overlying said sets of drawers, a typewriter-support in said well, supporting means for said typewriter-support including rock-shafts extending from the well through the pedestals between adjacent drawers, a T-shaped cover to close the opening in said top, supporting means for said cover comprising two links at each end of the desk, pivoted to the adjacent extension of the cover, so that the latter may be swung from horizontal closed position to a substantially vertical position in the back of the desk, and a connection between one cover-supporting link at each end of the desk and the outer end of the adjacent rock-shaft, whereby movement of the cover to open the desk will cause the typewriter-support to be moved upwardly, and movement of the cover to closed position will cause the typewriter-support to be lowered.

2. In a typewriter-desk, in combination, two pedestals, each containing a set of drawers, spaced apart to form a well therebetween, a desk-top having a T-shaped opening extending rearwardly from the front edge of the desk-top over said well and having lateral extensions at its rear end overlying said sets of drawers, a typewriter-support in said well, a typewriter carrier mounted on the support and slideable to a rearward position when the desk is to be closed and to a forward position when typing is to be effected, a mounting for said typewriter-support including rock-shafts extending from the well through the pedestals between adjacent drawers, a T-shaped cover to close the opening in the desk-top, supporting means for said cover comprising two links at each end of the desk pivoted to the adjacent extension of the cover, so that the latter may be swung from horizontal closed position to a substantially vertical position in the back of the desk, and a connection between one cover-supporting link at each end of the desk and the outer end of the adjacent rock-shaft, whereby movement of the cover to open the desk will cause the typewriter-support to be moved upwardly, and movement of the cover to closed position will cause the typewriter-support to be lowered.

3. In a typewriter-desk, in combination, two pedestals, each containing a set of draw-

ers, a top comprising a portion attached to said pedestals and provided with a T-shaped opening extending rearwardly over the opening between the pedestals and laterally at the rear of the desk, and a movable portion normally in position to close said opening but shiftable rearwardly and downwardly into the back of the desk, and means to close the lateral extensions of said T-shaped opening when the movable portion of the top is in depressed position.

4. In a typewriter-desk, in combination, two pedestals, each containing a set of drawers, a top comprising a portion attached to said pedestals and provided with a T-shaped opening extending rearwardly over the opening between the pedestals and laterally at the rear of the desk, and a movable portion normally in position to close said opening but shiftable rearwardly and downwardly into the back of the desk, and means to close the lateral extensions of said T-shaped opening when the movable portion of the top is in depressed position, the closing means for the lateral extensions of the T-shaped opening comprising a member pivoted at the rear edge of the desk and normally extending downwardly at the rear of said desk.

5. In a desk for use with a typewriter and a sound-deadening casing, in combination, two drawer-containing pedestals spaced to provide a well therebetween, a top having an opening extending rearwardly over said well and laterally at its rear end over said pedestals which are cut away therebeneath to receive the sound-deadening casing, a T-shaped cover to close said opening, a typewriter-and-casing support within said well, and means, including connections between said cover and the pedestals on the outer side of the sets of drawers and connections between the typewriter-and-casing support and the pedestals between the sets of drawers, whereby movement of the cover to ineffective position will cause movement of the typewriter-and-casing support to effective position, and movement of the cover to closed position will cause the support to be moved to ineffective position.

6. In a typewriter-desk for use with a sound-deadening casing having a base and portions projecting laterally from the upper part thereof, in combination, two drawer-containing pedestals spaced to form a well of sufficient width to receive said base, a slideable support mounted between said pedestals so that, when it is in effective position with the base of said casing thereon, the laterally-projecting portions of the casing will overlie the pedestals, a desk-top having an opening between said pedestals to receive the base of the casing and provided with lateral extensions at its rear to permit the laterally-projecting portions of the casing to pass therethrough in the rear of the drawers

when the casing has been slid to the rear on said support, and means for causing the casing to be lowered substantially vertically into the desk.

7. In a typewriter-desk for use with a sound-deadening casing having a base and portions projecting laterally from the upper part thereof, in combination, two pedestals spaced to form a well of sufficient width to receive said base, a slidable support mounted between said pedestals so that, when it is in effective position with the base of said casing thereon, the laterally-projecting portions of the casing will overlie the pedestals, a desk-top having an opening between said pedestals to receive the base of the casing, said opening having lateral extensions at its rear to permit the laterally-projecting portions of the casing to pass therethrough when the casing has been slid to the rear on said support, means whereby said opening may be closed when said casing has been lowered below said desk-top, and means to close the lateral extensions of said opening when the typewriter-support is in effective position.

8. In a flat-top desk for use with a typewriter and a sound-deadening casing, a pair of pedestals having cavities in their upper rear portions for the reception of the sound-deadening casing when not in use, and draw-

ers in their front portions, a typewriter-and-casing support arranged to swing about a pivot adjacent its forward extremity to lower the casing into the cavities in the pedestals, and a typewriter-and-casing carrier slidable forwardly on the support to position the typewriter and casing in convenient writing position near the pivot of the support and slidable rearwardly to position the casing over the cavities and remote from the support-pivot.

9. In a flat-top desk for use with a typewriter and a sound-deadening casing, a pair of pedestals having drawers therein, a typewriter-and-casing support arranged to swing about a pivot adjacent its forward extremity, and a typewriter-and-casing carrier slidable forwardly on the support to position the typewriter and casing in convenient writing position at the front of the desk and near the pivot of the support, and slidable rearwardly to position the casing over the rear of the desk beyond the rear ends of the upper drawers and remote from the pivot of the support, so that swinging movement of the support will impart a substantial bodily movement to the typewriter and casing to lower them into the desk, the desk having cavities in the upper rear portions of its pedestals behind the upper drawers.

BURNHAM C. STICKNEY.
